VALVE DIAPHRAGM OR THE LIKE

Edmond Robert Parfonny, Brussels, Belgium, assignor to
Societe Industrielle d'Etudes et de Realisations Scien-
tiques, Paris, France, a corporation of France

Filed July 28, 1961, Ser. No. 66,112

Term of patent 14 years

(Cl. D78—1)

FIG. 1

FIG. 2

FIG. 3

FIG. 4

FIGURE 1 is a perspective bottom view of the valve diaphragm or the like, the diaphragm being shown in re-
versed position, showing my new design;

FIG. 2 is a front elevation thereof;

FIG. 3 is a top perspective view thereof; and

FIG. 4 is a top plan view thereof.

I claim:

The ornamental design for a valve diaphragm or the
like, as shown.
